(57) **CLAIM**

The ornamental design for a fixture for a pool or spa, as shown and described.

DESCRIPTION

FIG. 1 is a front elevational view of a fixture for a pool or spa showing our new design;

FIG. 2 is a right side elevational view thereof with the left side elevational, top and bottom plan views being mirror images; and,

FIG. 3 is a front perspective view thereof.

The broken lines in FIGS. 1-3 are for illustrative purposes only and form no part of the claimed design.

1 Claim, 3 Drawing Sheets

FIG. 1

FIG. 2

FIG. 3
